UNITED STATES PATENT OFFICE.

DAVID J. SMITH, OF FINSBURY PARK, LONDON, AND CHARLES TOWL, OF FOREST GATE, ENGLAND.

AUTOMATICALLY OPERATED AND CONTROLLED GAS-GENERATOR.

1,268,290.

Specification of Letters Patent.

Patented June 4, 1918.

Application filed August 4, 1916. Serial No. 113,119.

To all whom it may concern:

Be it known that we, DAVID JOSEPH SMITH, a subject of the King of Great Britain, and a resident of 40 Woodberry Grove, Finsbury Park, London, N., England, and CHARLES TOWL, a subject of the King of Great Britain, and a resident of 155 Earlham Grove, Forest Gate, Essex, England, have invented new and useful Improvements 10 in or Connected with Automatically Operated and Controlled Gas-Generators, of which the following is the specification.

This invention relates to improvements in or connected with automatically operated 15 gas generators, and in particular to an improved construction and arrangement of automatically operated and controlled acetylene gas generator.

The object of this invention is to provide 20 an improved construction of gas generator especially those for the production of acetylene gas from carbid of calcium, for the purpose of generating such gas automatically only when required for supplying and controlling the supply to a gas holder or gasometer or for maintaining a uniform supply 25 of gas for lighting, welding, or any similar purpose. A number of generators may be used and the water supply to the tank controlled by the pressure of gas or other known 30 method, so that as the pressure falls, water is admitted to the tank of the generators in succession.

Our apparatus may also be employed for 35 operating known mechanism by the pressure of the gas, for example, bulkhead doors, sluice gates or the like, or for the purpose of charging and releasing buoys for signaling or other purposes, or for raising telegraph 40 or signaling arms or otherwise operating signals. An additional object of the invention is to provide such a construction of the generator that the carbid of calcium or the like is held out of reach of the water until 45 the entry of the latter has occurred in such volume as to insure that the acetylene shall be rapidly generated and more effectively operate the said mechanism.

We provide in a closed casing a tank for 50 water, preferably formed as a cylinder, which is provided on its exterior with longitudinal flanges or webs bearing upon the interior of a cylindrical portion of the casing, which latter therefore acts as a guide. A 55 rod is rigidly secured in the bottom of the

said tank and extends in the axial line through same, the upper end being adapted to slide in a closed end guide in the upper part of the casing. Mounted concentrically upon the the said rod and adapted to slide 60 easily thereon is a cylindrical receptacle for carbid formed of wire gauze, perforated metal or the like. The receptacle is provided with a central tube fitting the said rod, and with a disk at its lower end which serves 65 as a valve fitting a seating to hold closed the upper part of the casing in which the carbid receptacle is suspended. The said rod extends through the bottom of the water tank and rests upon one end of a lever, serving 70 as a support for the said tank, fulcrumed in the base of the closed casing. The other end of the lever supports a rod extending upwardly vertically in the closed casing and adapted to slide in guides provided therein. 75 The said rod carries a weight rigidly secured thereto, also preferably inclosed in the casing, which serves to balance by means of the said lever the water tank supported on the other end of the balanced lever plus a cer- 80 tain predetermined quantity of water. Secured on the said weight rod is a valve adapted to close the passage for the inlet of water, which is arranged in the outer casing just above the valve seating. The said inlet is preferably covered with wire gauze or 85 perforated metal.

The said carbid receptacle is provided at its upper end, fitted to slide on the central tube, with cross-head pins having a spring 90 between same and the collar at the end of the tube. When the apparatus is charged and set for operation, the cross-head pins are supported by the forked end of a bell-crank lever fulcrumed in the casing. The said 95 collar also abuts when in the set position against a collar secured on the central rod of the water tank.

The said bellcrank lever co-acts with a second lever arm fulcrumed in the casing, 100 having a fork at its end engaging a pin fixed in the said weight rod. The lever arm has secured therein a pin which serves to hold the upper end of the bellcrank lever. The two levers and the said pin constitute a 105 trip or trigger mechanism, to release the said suspended carbid cylinder when the predetermined weight of water in the said tank has been exceeded.

The apparatus operates as follows: When 110

water flows into the said inlet, it is conveyed by the open valve into the water tank. When the weight of the rising water in the tank, plus that of the tank, overbalances that of the balance weight, the tank arm of the lever in moving down lifts the weight on the other arm and thereby lifts the pin on the weight lever from its holding engagement with the upper arm of the bellcrank lever, 10 the other end of which no longer supports the carbide cylinder, which thereupon falls into the water tank, and the gas is rapidly generated. The added weight of the carbide in the tank lifts the balance weight still farther, and the valve fitted to the balance rod closes on its seating preventing the outlet of gas thereby and the further inflow of water.

In a modified construction, the valve may 20 be carried on an arm secured to the balance weight rod, or in a further modification a flap valve may be adapted to close the water inlet, the said flap valve being connected by a link or links to the balance or weight rod. 25 Any number of generators may be employed adapted by these means to come into operation in succession, thus allowing the recharging of the empty or used generators, while others are supplying or ready to supply the gas holder in their turn.

And in order that our invention may be completely understood reference should be made to the accompanying sheet of drawings which illustrates one example of this 35 invention:—

Figure 1 is a sectional elevation of the apparatus showing the carbide receptacle lifted out of the water and the trigger set to be released.

40 Fig. 2 is a similar elevation but with the trigger released, and the carbide receptacle dropped into the water tank.

1 is the carbide receptacle formed of wire gauze. 2 is the water tank. The water tank 45 and carbide receptacle have passing through them centrally fitted the rod 3, which is held in the guide 4 at the top of the casing, and rests at its lower end 5 on the end of the arm 6 of the balance lever, which is fulcrumed at 50 8 in the casing of the apparatus. The other end 7 of the balance lever supports the lower end of a rod 9 which is fitted into the slot 10 in the lever arm.

This rod is retained by the guides 11 and 55 12. It carries the water admission valve 13 and passes through the guide 14 into the cylindrical receptacle 15 which contains the balance weight 16. The weight 16 is secured to the rod 9 which fits and is adapted to slide 60 in the guide 17 provided at the top of the cylinder 15. The rod 9 is connected by cross pins 18 to the lever 19 which is fulcrumed at 20. The lever 19 is provided with the projecting pin 21 which is adapted to engage 65 one end 22 of the bell crank lever fulcrumed

at 23 and the other arm of the lever is provided with a fork 23^a adapted to embrace and partly surround the tube 24 which is fixed to the carbide receptacle 1. The tube 24 surrounds and is adapted to slide on the 70 tube 3. The upper end of the tube 24 has fitted thereto a loose collar carrying the crosshead pin 25, and between the collar of the crosshead pins and the shoulder 26 on the end of the tube 24, is the spring 27. Each 75 arm of the said fork 23^a engages a crosshead pin and is provided with a projection 28 to prevent the pins when in position from turning. The spring is thus compressed between the said collar and shoulder when the bellcrank trigger is in the operative position. When in this position the bellcrank lever forks support the carbide receptacle 1 in its 80 upper position, see Fig. 1, since the other end of the lever is held by the pin 21 on the 85 lever 19.

It will be observed that in this position the valve 30 formed on the bottom of the carbide receptacle 1 fits the seating 31 and closes the upper part of the cylinder 32 from 90 the lower part 33 in order to keep the water vapor from entering the upper part and deteriorating the carbide.

The pipe 34 is the outlet for the acetylene gas and the port 35 is that for the admission 95 of water.

Referring to Fig. 2, when the water rises outside the apparatus to the level of the water inlet 35, the valve 13 being held off its seat 13^a as in Fig. 1, the water flows freely 100 by the passage 36 into the water tank 2, and on nearly filling the same, the weight of the water and tank overbalances the weight 16 supported on the other side of the balance weight lever 6—7. The bellcrank lever 105 22—23^a is thus released, since the falling of the water tank 2 and the carbide causes by means of the balance lever fulcrumed at 8 the rod 9 and the weight 16, the lever 10 to be lifted, and thereby the pin 21 is released 110 from engagement with the end of the upper arm 22 of the bellcrank lever. This permits the bellcrank lever to fall, which releases the engagement of the fork at the other end 115 with the carbide receptacle 1, which at once falls into the water in the tank 2, and this takes then the position shown in Fig. 2, the gas generated passing out rapidly through the outlet pipe 34. On the other hand by the 120 rise of the rod 9, the valve 13 closes on its seat 13^a, and thus not only prevents the entry of any further water but also prevents the passage of any gas by the valve 13.

The nut 3^a is set in such a position on the rod 3 that in the event of the carbide receptacle or cage "sticking" the downward movement of the rod will bring the whole weight of the water contained in the cylindrical tank 2 to bear on the carbide receptacle in order to release it.

What we do claim as our invention and desire to secure by Letters Patent is:—

1. In an automatically operated gas generator, the combination of a water tank supported for movement and adapted to move downward when a predetermined quantity of water is received therein, a carbide holder movable relatively to the water tank and adapted to normally occupy a position outside of the water tank and to move into the water tank, trip mechanism for supporting the carbide holder in normal position outside of the water tank, and means operatively connected with the water tank and adapted upon downward movement of the water tank to release said trip mechanism and permit the carbide holder to move into the water tank.

2. In an automatically operated gas generator the combination of a casing provided with an inlet for water and an outlet for gas, a valve for the water inlet, a water tank movably supported within the casing to receive water from the water inlet and adapted to move downwardly when a predetermined quantity of water is received therein, a carbide holder in the casing supported for movement relative to the water tank, said carbide holder being adapted to normally occupy a position outside of the water tank and to move into the water tank, trip mechanism for supporting the carbide holder in its normal position outside of the water tank, and means actuated through the downward movement of the water tank to operate the valve to close the water inlet and to operate said trip mechanism to release the carbide holder and permit the same to move into the water tank.

3. In an automatically operated gas generator, the combination with a casing, a water tank in the casing, a chamber within the casing above the water tank, said chamber having an opening at the bottom thereof and having a gas outlet, a carbide holder within the casing supported for movement vertically into said chamber and the water tank and adapted to normally occupy a position within said chamber, a water supply conduit leading into the casing to the water tank, and a valve connected with the carbide holder, said valve closing the opening at the bottom of the chamber when the carbide holder is positioned within said chamber, trip mechanism for supporting the carbide holder in normal position within said chamber, and means acting automatically when a predetermined quantity of water is received in the water tank to operate the trip mechanism to release and permit the carbide holder to drop into the water tank.

4. In an automatically operated gas generator, the combination of a lever pivoted intermediate its ends, a weight connected with one end of the lever, a water tank

mounted for vertical sliding movement and supported on the other end of said lever, a carbide holder supported for vertical sliding movement and adapted to normally occupy a position above the water tank and to move downwardly into the same, trip mechanism to maintain the carbide holder in elevated position above the water tank, and a connection between the lever and said trip mechanism, said water tank being adapted to move downwardly against the action of the weight when a predetermined quantity of water is received therein, and through said downward movement to tilt the lever and release the trip mechanism to permit the carbide holder to move downwardly into the water tank.

5. In an automatically operated gas generator, the combination of a lever pivoted intermediate its ends, a rod supported for vertical sliding movement and pivotally connected with and extending upwardly from one end of the lever, a weight on the rod, a water tank mounted to slide vertically and supported upon the other end of the lever, a water supply conduit leading to the water tank, a valve on the rod controlling the water supply conduit, a carbide holder supported for vertical sliding movement, and adapted to normally occupy a position above the water tank and to move downwardly into the same, trip mechanism for maintaining the carbide holder in its elevated position above the water tank, and an operative connection between the lever and said trip mechanism, the water tank being adapted to move downwardly against the action of the weight when a predetermined quantity of water is received within the same, and through said downward movement to operate the valve to close the water supply conduit and to release the trip mechanism and permit the carbide holder to descend into the water tank.

6. In an automatically operated gas generator, a water tank supported for vertical sliding movement and adapted to move downwardly when a predetermined quantity of water is received within the same, a rod secured to the water tank and extending above the same, a carbide holder slideable upon said rod and adapted to normally occupy a position above the water tank and to move downwardly into the water tank, trip mechanism for maintaining the carbide holder in its normal elevated position above the water tank, means controlled through the downward movement of the water tank to release the trip mechanism and permit the carbide holder to descend into the water tank, and an abutment on said rod adapted to engage and force the carbide holder downwardly upon the downward movement of the water tank.

7. In an automatically operated gas gen-

erator, the combination of a water tank, and carbid feeding mechanism including carbid holding means, trip mechanism operably associated therewith and operable by the weight of the water in the water tank to release the carbid holding means and permit carbid to fall into the water in the water tank.

8. In an automatically operated gas generator, the combination of a water tank, and carbid feeding mechanism including a

carbid holder and means for suspending the carbid holder including trip mechanism operable by the weight of the water in the water tank to release the carbid holder and 15 permit the same to fall into the water tank.
